UNITED STATES PATENT OFFICE.

HOWARD STILLMAN, OF BERKELEY, CALIFORNIA.

DIAPHRAGM FOR NON-VESTIBULE PASSENGER-TRAIN CARS.

1,172,749.

Specification of Letters Patent. Patented Feb. 22, 1916.

Application filed September 9, 1915. Serial No. 49,685

To all whom it may concern:

Be it known that I, HOWARD STILLMAN, of Berkeley, in the county of Alameda and State of California, have invented a certain new and useful Improvement in Diaphragms for Non-Vestibule Passenger-Train Cars, of which improvement the following is a specification.

In present standard railroad practice, passenger train cars for through or long distance service are generally, if not universally, provided with end vestibules, comprising a face plate which abuts against a corresponding plate on an adjoining car, and a flexible diaphragm of the bellows type, formed of stout canvas and interposed between the face plate and the car end. These flexible diaphragms extend vertically and also transversely overhead, in order to protect passengers from the weather when passing from one car to another of a train, and provide for compression and relative movement of two cars when coupled together. On head end or baggage and mail cars, the abutting face plates are similarly combined with flexible diaphragms, but it is not found necessary to extend them transversely for overhead protection, as there is but little passage between these cars, and such as there is, is only by employees on duty on the train.

Much trouble has been experienced and loss incurred by reason of the canvas diaphragms of head end or non-vestibule cars being cut open by tramps and other trespassers who climb between these head end cars for the purpose of stealing rides or entering the cars for purposes of robbery, etc., and so many diaphragms have been damaged in service that, on an important railroad system, it has been considered advisable to remove them from head end cars. It is, however, desirable that a flexible protecting medium for passage from car to car should, if practicable, be applied, and the object of my invention is to provide a device of such character which shall be of simple and inexpensive construction and ready applicability, and be practically burglar proof.

The improvement claimed is hereinafter fully set forth.

In the accompanying drawings: Figure 1 is a side view, in elevation, of the adjoining end portions of two head end or non-vestibule cars, illustrating an application of my invention; Fig. 2, a similar view, on an en-

larged scale, of a diaphragm, and Fig. 3, a horizontal section, on a further enlarged scale, taken on the line $\alpha\alpha$ of Fig. 2.

Referring to the drawings, in the practice of my invention each side of the vestibule face plate, 1, of a head end or non-vestibule passenger train car, A, which face plate, as heretofore, is adapted to abut against a corresponding plate on an adjoining car, B, is flexibly or yieldingly connected to the end framing, α , of the car by an articulated metallic diaphragm, comprising two plates, 2 and 3, of sufficient thickness to afford substantial protection from penetration by a cutting instrument, as, say 3/32 inch steel, and hinges by which said plates are pivotally connected to the end frame of the car and to the face plate, 1, respectively, and, at their adjoining ends, are similarly connected one to the other. The plates, 2 and 3, are outwardly inclined, and disposed at substantially similar angles to the end frame and to the face plate, respectively, and therefore at an angle one to the other, and one of them, in the instance exemplified, the plate, 3, is made slightly wider than the other, in order to cover the space at their meeting angle, as shown in Fig. 3.

Hinge straps, 4, preferably of malleable iron, each having a socket, 4^a , on one of its ends, are secured to the face plate, 1, and similar straps, 5, each having a socket, 5^a , on one of its ends, are secured to the end frame, α , of the car. Hinge straps, 6, also preferably of malleable iron, having sockets, 6^a , on their opposite ends, are riveted to the diaphragm plates, 1 and 2, the straps of one of the diaphragm plates, as 2, being pivotally connected to the end frame straps, 5, by pins, 7, passing through the adjoining sockets, and the straps of the other diaphragm plate, as 3, being similarly connected to those of the face plate, 1, by pins, 7^a . The plates, 2 and 3, are pivotally connected one to the other, by a rod, 8, passing through the sockets at the adjacent ends of the hinge straps, 6. It will be seen that movement of the diaphragm plates under lateral and longitudinal variation of relative position of coupled cars, is provided for by the hinge pins, 7 and 7^a , and rod, 8, and in order to admit of variation of relative vertical movement, due to inequalities in the track, the members of each pair of hinge straps, 6, of the diaphragm plates, 2 and 3, are spaced apart, vertically, one from

another. In other words, each of the hinge straps of one diaphragm plate is disposed at a short distance above or below the companion hinge strap of the other diaphragm plate.

My improvement is of substantial practical advantage, in rendering burglar proof, under the conditions of service, the space between two coupled cars, and preventing unauthorized entrance thereinto, as well as eliminating the cost of renewal of the ordinary canvas bellows type diaphragms when mutilated by trespassers or thieves. It will, however, be obvious that, if desired, it may be applied in connection with sections of the latter type and will effect a corresponding reduction in their dimensions.

I claim as my invention and desire to secure by Letters Patent:

1. The combination, with a railroad car, of a diaphragm face plate, two metallic diaphragm plates, hinge straps secured to said

diaphragm plates, hinge straps secured to the face plate, hinge straps secured to the car end, and pivotal connections coupling 25 the diaphragm plates, through the several hinge straps, one to the other and to the face plate and car end, respectively.

2. The combination, with a railroad car of a diaphragm face plate, two metallic dia- 30 phragm plates, hinge straps secured to said diaphragm plates, the opposite hinge plates being spaced apart vertically, hinge straps secured to the face plate, hinge straps secured to the car end, and pivotal connections 35 between the car end straps and the straps of one of the diaphragm plates, between the face plate straps and those of the other diaphragm plate, and between the straps of the two diaphragm plates.

HOWARD STILLMAN.
